Primary Examiner — Mitchell I. Siegel*(74) Attorney, Agent, or Firm* — Rebecca Hanovice; Michael Catania; Sonia Lari(57) CLAIM

The ornamental design for a golf club hosel, as shown and described.

DESCRIPTION

FIG. 1 is a side perspective view of the golf club hosel claimed herein;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof; and,

FIG. 7 is a bottom elevational view thereof.

The broken lines are included for the purpose of illustration and form no part of the claimed design.

1 Claim, 4 Drawing Sheets(56)
